US00D332839S

United States Patent [19]

Beckner, Jr.

[11] Patent Number: Des. 332,839

[45] Date of Patent: ** Jan. 26, 1993

[54] BATTERY POWERED PURSE OR CASE
LIGHT

4,954,934 9/1990 Kidder et al. .
4,972,304 11/1990 Ylla .

[76] Inventor: Kenneth W. Beckner, Jr., 3520
Cleveland Heights Blvd., Lakeland,
Fla. 33802

FOREIGN PATENT DOCUMENTS

146002 6/1936 Austria 362/201

[**] Term: 14 Years

Primary Examiner—Susan J. Lucas

Attorney, Agent, or Firm—Frijouf, Rust & Pyle

[21] Appl. No.: 719,541

CLAIM

[22] Filed: Jun. 24, 1991

The ornamental design for a battery powered purse or
case light, as shown and described.

[52] U.S. Cl. D26/37

DESCRIPTION

[58] Field of Search D26/37-50;
362/103, 154, 155, 156, 157, 158, 183-191,
194-202, 205

FIG. 1 is a perspective view of a first embodiment of my
new design for a battery powered purse or case light
showing the rear, top and left side thereof;

FIG. 2 is a top plan view thereof;

FIG. 3 is a bottom plan view thereof;

FIG. 4 is a right end elevational view thereof;

FIG. 5 is a left end elevational view thereof;

FIG. 6 is rear elevational view thereof;

FIG. 7 is a front elevational view thereof;

FIG. 8 is a perspective view of a second embodiment of
my new design for a battery powered purse or case light
showing the rear, top and left side thereof;

FIG. 9 is a top plan view thereof;

FIG. 10 is a bottom plan view thereof;

FIG. 11 is a right end elevational view thereof;

FIG. 12 is a left end elevational view thereof;

FIG. 13 is rear elevational view thereof; and,

FIG. 14 is a front elevational view thereof.
